Inventor
John Anton Kulier
By his Attorney C. P. Goepfert

UNITED STATES PATENT OFFICE.

JOHN ANTON KULMER, OF BROOKLYN, NEW YORK.

WINDOW-RAISING DEVICE.

1,372,171. Specification of Letters Patent. Patented Mar. 22, 1921.

Application filed July 2, 1920. Serial No. 393,678.

To all whom it may concern:

Be it known that I, JOHN A. KULMER, a citizen of the United States, and a resident of the borough of Brooklyn, in the city, county, and State of New York, have invented certain new and useful Improvements in Window-Raising Devices, of which the following is a description.

The present invention relates to window raising devices, and particularly such devices for raising and lowering the windows of motor car doors, railway coaches and the like, an object of the invention being to provide improvements in that type of window-raising device in which lazy tongs are employed, it being proposed to provide novel means for conveniently operating the lazy tongs, and maintaining the same at any position of adjustment without the necessity of performing an additional securing operation, or providing special means distinct from the raising means therefor.

A further object is to provide a construction in which a final adjustment of the glass panel may be effected at the end of its raising and lowering movement, the means being such as to permit of a relatively smaller glass panel being used than has heretofore been possible, and enabling the panel to be automatically forced tightly into place at the end of the raising movement, so that a very tight closure results.

It is further proposed to provide a raising means which will be extremely facile to operate, requiring very little effort to raise or lower the window, and further, to provide a construction especially adapted for automobile door use, the same being compact and resistant to the unusual conditions of use and strain put upon such doors.

With these and other objects in view, an embodiment of my invention is shown in the accompanying drawings, and this embodiment will be hereinafter more fully described with reference thereto, and the invention will be finally pointed out in the claims.

In the accompanying drawings:

Figure 1 is a view in elevation of the device, showing the same mounted upon a frame, which may be incorporated in a door, or in a window construction, and with the outer wall removed and certain parts broken away,

Fig. 2 is a vertical view taken along the lines 2-2 of Fig. 1, and,

Fig. 3 is a detail view of the rear side of the handle.

Similar reference characters designate corresponding parts throughout the several views of the drawings.

Referring to the drawings, the glass panel 10 is slidable vertically in grooves 11 and 12, provided upon the inner sides of the uprights 13 and 14 of the frame, said uprights 15 being connected at their lower ends to a base rail 15, and at their upper ends to a slotted sill 16, the glass panel 10 adapted to be raised through the slotted sill, and in the lowered position thereof, to have its upper edge substantially flush with the sill. It will be understood that suitable means may be provided upon the sill for effecting a water-tight closure, when desired, and also a protective strip may be provided along the upper edge of the glass panel, but it is not deemed necessary to show such features, as they do not enter into the invention. The lower edge of the glass panel is engaged by a channeled member 17 connected, as will hereinafter more fully appear, to the means for effecting the raising and lowering of the panel.

A sheet metal plate 18 extends between the base rail 15 and the sill 16, being secured thereto by screws 18*, and at the lower end of the said plate there is provided a supporting shelf portion 19 bent at right angles therefrom, and upon which there is supported a channeled track member 20 of U-shape in cross section, and provided at its upper ends with inwardly bent retaining flanges 21 and 22 to provide a restricted slot through which the lower lever arms 23 and 24 extend, and are provided with rollers 25 and 26, projecting beneath the said flanges, so that the ends of the rods may slide in the channel track and will not be lifted therefrom. The arms 23 and 24 are pivoted at 27, and at their ends are pivotally connected, the ends of arms 28 and 29 pivotally connected together at their centers, and pivotally connected at their other ends to the ends of arms 30 and 31, pivotally connected centrally, and pivotally connected at their other ends to arms 32 and 33, substantially half of the length of the said arms 30 and 31, and pivotally connected at their ends, thus forming a lazy tongs. To the pivot 27 of the lowermost arms 23 and 24 of the lazy tongs there is connected the end of an elongated bar 34 enlarged at its upper portion,

8325<br

as at 34^a, and guided vertically in a series of pairs of guide lugs 35, 36 and 37, struck up from the plate 18, the lower end of the arm being offset from the plate 18, so as to space the lazy tongs in such manner that when it is raised it will clear certain parts of the device, hereinafter referred to. A cut-out portion 39 is provided in the channel track 20, into which the lower end of the bar 34 moves in the extreme lowered position thereof.

The portion 34^a of the slide bar is provided with an interior opening 40 at its upper portion substantially rectangular in shape, and with an open portion 41 extending downwardly therefrom, and provided at each of its opposed edges with pitched teeth 42 engaged by a worm 43, provided upon a shaft 44 journaled at its ends in bearing brackets 45 and 46 struck up from the plate 18. At the upper end of the shaft 44 there is provided a gear 47 projecting through an opening 48, provided in the plate 18. The plate 18 is provided with a depression 49, in which the shaft 44 is disposed, and also with a socket portion 50, in which the worm 43 is disposed, so that the bar 34 may lie against the inner side of the plate 18, and at the same time the axis of the shaft 44 will be in line with the central plane of the said bar, and thus insure a proper engagement of the worm with the pitched teeth 42.

Upon a stud 51 mounted upon the plate 18 above the gear 47 there is rotatably mounted a handle 52, removably secured to the stud by means of a screw 53, and provided with an enlarged hub portion 54, provided with a recess 55 at its inner side, in which there is disposed a plate 56, having a plurality of radially disposed cut-outs 57, the solid portions of the plate between the cut-outs constituting gear teeth engaging the teeth of the gear 47.

By turning the handle, the shaft 44 and the worm 43 carried thereby are rotated, and thus the bar 34 is caused to be raised or lowered, expanding or contracting the lazy tongs, and at the same time is of such construction as to maintain its position of adjustment.

The channel piece 17, in which the glass panel rests, is provided with a depending arm 58, having a vertical slot 59 therein, engaging a stud 60, forming the pivotal connection of the upper arms 32 and 33 of the lazy tongs. At each side of the pivot 60, and upon the arms 32—33 there are pivotally mounted lever arms 61 and 62, their short arms intersecting and being provided with elongated slots 63 and 64 engaged by pins 65 provided at the end of the arm 58. In the lowered position of the glass panels the outer ends of the arms 61 and 62 are engaged by stops 66 and 67, provided upon the outer wall 68 of the door or window casing, and are moved by such stops to the po-

sition indicated in full lines in Fig. 1, and in which position the glass panel is brought to a final adjustment independent of the action of the lazy tongs, causing the same to be carried lower in the window casing than would be possible with the action of the lazy tongs alone. When the panel is raised to close the window, the arms 61 and 62 engage the under side of the sill 16 as the lazy tongs approaches the extent of its raising movement, and causes a relative raising of the glass panel relatively to the end of the lazy tongs, so that a final raising movement of the glass pane results, which tightly closes the same. This construction, it will be seen, enables the use of a glass panel of smaller area than is used in connection with the raising and lowering devices heretofore in use.

In the sill 16 there are provided cut-out portions 69 and 70 adapted to receive the channel member 17 and the upper end of the bar 34 in the raised position indicated in dotted lines.

I have illustrated and described a preferred and satisfactory embodiment of my invention, but it is obvious that changes may be made therein within the spirit and scope thereof, as defined in the appended claims.

I claim:

1. In combination with a window frame and a transparent panel slidable therein, of supporting means fitting the lower edge of said panel, substantially vertically extensible lazy tongs within the window frame beneath said panel and connected at its upper portion to said supporting means, a bar disposed substantially vertically in the window frame and having its lower end connected to the lower portion of said lazy tongs, guide means in the window frame for the upper portion of said bar, said bar being provided with worm teeth, a substantially vertically disposed shaft in said window frame, a worm thereon meshing with the worm teeth of said bar, and means on the exterior of the window casing adapted to rotate said shaft.

2. In combination with a window frame and a transparent panel slidable vertically therein, supporting means engaging the lower edge of the panel, a lazy tongs having its upper end pivoted to said supporting means and having its lower arms slideable transversely along the base of the window frame, a substantially vertically reciprocating bar in said window frame having its lower end connected to the lower portion of said lazy tongs and being slotted at its upper portion and provided with oppositely disposed series of worm teeth, guide means for the upper portion of said bar, a substantially vertically disposed shaft journaled in the window frame and lying within the slot in said bar, a worm on said shaft

meshing at opposite points with said two series of worm teeth, a pinion also on said shaft, and a manually rotatable gear wheel on the exterior of said window frame in 5 mesh with said pinion.

3. In combination with a frame and a movable panel therein adapted to be raised and lowered, raising and lowering means for the panel, supporting means for the panel 10 carried by said raising and lowering means, and having limited vertical movement relatively thereto, and means carried by said raising and lowering means adapted to produce relative raising and lowering movement of said raising and lowering means. 15
4. In combination with a frame and a

movable panel therein, adapted to be raised and lowered, a lazy tongs adapted to be expanded and contracted, supporting means for the panel carried by said lazy tongs, and 20 having limited vertical movement relatively thereto, lever arms carried by said lazy tongs and operatively connected to said supporting means, and stop means adapted to engage said lever arms at the ends of the raising and lowering movement of said lazy tongs to cause raising and lowering movement of said supporting means relatively to 25 said lazy tongs.

In testimony that I claim the foregoing as my invention, I have signed my name.

JOHN ANTON KULIER.
